ELECTRONIC ACCOUNTING MACHINE

Carl F. Rensch, Troy, Ohio, assignor to The National Cash Register Company, Dayton, Ohio, a corporation of Maryland

Application December 17, 1949, Serial No. 133,540

5 Claims. (Cl. 250—27)

1

This invention relates to electronic accounting machines and in particular to an improved controlled digital electronic impulse generator and accumulator with readout and digit-manifesting means therefor.

The novel impulse generator is of a type which is capable of effecting entries simultaneously in a plurality of denominational orders of an accumulator. The impulse generator utilizes a plurality of tubes, which are common to a plurality of denominational orders, for producing impulse trains corresponding to the digits "1" to "9" and containing corresponding numbers of impulses. These impulse trains, which are available to the plurality of denominational orders, may be selectively switched to any one or more denominational output conductors of the impulse generator by corresponding denominational digit-selecting means.

The plurality of tubes of the impulse generator includes an oscillator-controlled means for producing driving impulses, a chain of tubes containing a "start" tube and a priming tube for each of the digits "1" to "9," and an impulse-train-producing tube for each of the priming tubes. The priming tubes are driven by the driving impulses, once the "start" tube has been rendered conducting, and will become conducting one after another in sequence, beginning with the "9" tube and ending with the "1" tube. As each priming tube becomes conducting, it conditions a related impulse-train-producing tube also to respond to the driving impulses and produce an impulse train containing the number of impulses corresponding to the value of the priming tube. As soon as the impulse trains have been produced, the "start" tube and the priming tubes are returned to their non-conducting status and made ready for another amount-entering operation.

The impulse-train-tube circuit provides a low impedance source for the impulses which is capable of producing extremely strong impulses, so that their quality will not be impaired and they will be able to produce satisfactory operation of the accumulator even though the impulses are switched simultaneously to a plurality of denominational output conductors to cause entries to be made in corresponding orders of the accumulator. This circuit also minimizes cross-talk or interference effects between conductors forming the output circuits.

The oscillator of the impulse generator is also used to control a further impulse-generating means to provide tens-transfer-effecting impulses for causing tens transfer entries to be

2

made in the accumulator, when required, and in such a manner as not to interfere with the normal digital entries in the accumulator.

The novel accumulator is made up of a plurality of denominational orders, each order of which contains an electronic coupling device through which digit entries and tens transfers are made, a pair of tubes connected as a trigger pair and operable to effect tens transfers, and four pairs of tubes connected to operate as trigger pairs, each trigger pair being operable to an "on" condition and an "off" condition, and further connected for accumulating digit values in the decimal notation and representing the units digit of the accumulated sum in that order, by predetermined combinations of "on" and "off" conditions of the trigger pair. The connections between the four trigger pairs, by which they are enabled to count in the decimal notation, connect the trigger pairs in cascade and also provide certain feed-back circuits, whereby the last trigger pair of the cascade, upon its being turned "on," can cause an automatic operation of one of the previous trigger pairs in the cascade, and, upon its being turned "off," can cause an automatic operation of another of the previous trigger pairs in the cascade. By separating the feed-back circuits and utilizing the "on" and "off" condition of the last trigger pair of the cascade and by providing suitable isolation resistors in conjunction with the feed-back circuits, the operating characteristics of the accumulator are improved, and rectifiers or decoupling units of the semi-conductor or barrier layer type have lower back impedance, such as germanium crystals, can be used, thereby eliminating the need for using diodes as rectifiers or decoupling units. The trigger pairs of the cascade and the transfer mechanism can readily be preset to starting or zero condition by selectively causing a tube in each of the trigger pairs to be made to conduct by a preset circuit.

The data represented by the combinations of "on" and "off" conditions of each denominational order is "read out" by the readout and digit-manifesting means, which includes a motor-driven sensing switch and digit-manifesting means. The manifesting means is arrested in different digit-manifesting positions by control means controlled by the sensing of different potentials at points in a resistor network to which different combinations of potentials are applied according to the "on" and "off" condition of the cascaded trigger pairs, their being ten points, of which only that point will have a distinctive potential which corresponds to the digit represented by the par-

ticular combination of the "on" and "off" conditions of trigger pairs of the denomination. Inasmuch as the potentials of the points in the resistance network are derived from the cascaded trigger pairs, the control means, which controls the position of the digit-manifesting means and the sensing switch and which has the potentials of the points of the network applied thereto by the sensing switch, has a compensating means to insure against misoperation due to variations in potentials applied to the cascaded trigger pairs. This compensating means makes the operation of the readout and digit manifesting means very stable and insensitive to variations in supply potentials.

It is an object of the invention to provide an improved electronic accounting machine having a controlled impulse-generating means for producing strong signals to be utilized for making simultaneous entries in desired orders of a simplified accumulator.

A further object of the invention is to provide a low impedance source of impulses which can produce strong impulses whose quality will not be impaired when they are switched simultaneously to a plurality of denominational output conductors.

A further object of the invention is to provide an accumulator for counting in the decimal notation and having, for each denomination, four electronic devices connected in a circuit for representing the digits of the notation in combinational form, the circuit being arranged to allow greater latitude in the choice of components.

A further object of the invention is to provide a counting circuit utilizing, for each denomination, four electronic devices connected in cascade and having improved feed-back circuits in which decoupling devices having lower back impedance can be used.

A further object of the invention is to provide a counting circuit made up of four cascaded trigger pairs, each pair being operable to an "on" condition and to an "off" condition, and utilizing the turning of the fourth trigger pair of the cascade to "on" condition to send a feed-back pulse to one of the previous trigger pairs of the cascade operation thereof and utilizing the turning of the fourth trigger pair to "off" condition to send a feed-back pulse to another of the previous trigger pairs of the cascade to cause an operation thereof.

A further object of the invention is to provide a means for indicating amounts standing in an accumulator and to provide compensating means in the controls for the indicating means to compensate for variations in voltage applied to the accumulator.

With these and incidental objects in view, the invention includes certain novel features of construction and combinations of parts, a preferred form or embodiment of which is hereinafter described with reference to the drawings which accompany and form a part of this specification.

Of the drawings:

Figs. 1-A and 1-B together show a circuit diagram of an impulse generator and the controls therefor.

Fig. 2 shows a circuit diagram of the units denominational order of the accumulator, including tens transfer means and the coupling device through which entries can be made from the impulse generator of Figs. 1-A and 1-B, and also shows digit-manifesting means for making apparent the digit set up in the accumulator.

Fig. 3 shows a circuit diagram of the tens denominational order of the accumulator and the digit-manifesting means therefor but includes controls for the coupling device through which entries can be made from the impulse generator of Figs. 1-A and 1-B and from the transfer means of Fig. 2.

In order that the invention may be explained more fully, a preferred embodiment of the invention will be described, in which description values of potential and circuit elements, such as resistors and capacitors, will be given and types of tubes will be specified. It is not intended, however, to limit the invention to the embodiment described nor to limit the circuit values and tube types to those specified, because these are merely selected as illustrative. It is obvious that other potentials and/or other similar tube types can be used and the circuit values of resistance and capacitance can be adjusted to maintain the proper relation between the various parts of the circuits. Throughout the circuit diagrams, the heater elements for the tubes are shown conventionally.

Impulse generator

The impulse generator is capable of generating impulse trains containing different numbers of impulses corresponding to the digits of the notation in which computations are to be made, and is capable of sending the required number of impulses over one or more output conductors according to the digits desired to be entered into the various denominations of the accumulator. The impulse generator and its controls are shown in Figs. 1-A and 1-B.

A multi-vibrator type oscillator consisting of tubes 11 and 12 (Fig. 1-A) is provided to drive the impulse generator and to coordinate the operation on the tens transfer means of the accumulator with the digit entries. These tubes have their anodes 13 and 14 connected over points 15 and 16 and resistors 17 and 18, of 22,000 ohms each, to conductor 19, which extends to terminal 20, to which a potential of +250 volts is applied. The cathodes 21 and 22 of these tubes are grounded. The grid 23 of tube 11 is coupled over capacitor 24, of 50 micro-microfarads, to point 16 in the anode circuit of tube 12 and also is connected to ground over a 1-megohm resistor 25. Similarly, grid 26 of tube 12 is coupled over capacitor 27, of 50 micro-microfarads, to point 15 in the anode circuit of tube 11 and also is connected to ground over resistor 28 of 1 megohm. While tubes 11 and 12 are shown, and function, as two separate tubes, they need not be separate but can be the two sections of a single tube such as may be purchased from Radio Corporation of America under type designation 12AU7. With the values given, and using the 12AU7 type of tube, the oscillator will oscillate at about 7,500 cycles per second, and points as 15 and 16 will make a like number of positive potential excursions.

Point 16 is coupled over a capacitor 30 of 250 micro-microfarads to grid 31 of a driving impulse generating tube 32. Tube 32, which is shown as a separate tube but which preferably is a half of a twin triode, such as a tube sold by Western Electric Company under the type designation 2C51, is normally biased to cut-off by having its grid 31 connected over a resistor 33 of 150,000 ohms and over conductors 34 and 35 to terminal 36, to which -30 volts is applied, and is allowed to conduct momentarily each time the potential of point 16 becomes sufficiently positive in the

operation of the oscillator to overcome the negative bias on the grid 31.

Tube 32 has its anode 37 directly connected to the conductor 19, to which +250 volts is applied, and has its cathode 38 connected to ground by a relatively low impedance circuit including point 39 and resistor 40 of 4,700 ohms.

With the values given, a positive potential impulse will be produced at point 39 each time tube 32 conducts momentarily, and these impulses are used to cause the sequential operation of a chain of priming tubes and to drive the impulse-train-producing tubes.

The chain of priming tubes (Figs. 1-A and 1-B) utilizes gaseous tetrodes, such as tubes sold by General Electric Company under type designation GL5663, and includes a "start" tube and a priming tube for each of the digits "1" through "9."

The "start" tube (Fig. 1-A) has its anode 45 connected directly to an anode potential supply conductor 46, which normally has a potential of +125 volts supplied thereto from point 47 in the cathode circuit of an extinguishing tube 48.

The control grid 49 of the "start" tube is normally biased to prevent conduction in the tube by being connected over resistor 50, of 47,000 ohms, point 51, and resistor 52 of 1 megohm to terminal 53, to which a potential of -30 volts is applied.

The cathode 60 of the "start" tube is given a potential slightly more negative than ground when the tube is non-conducting. This potential is obtained by connecting the cathode at point 61 in a resistance-capacitance network extending from point 62 on conductor 63, to which a potential of -108 volts is applied at terminal 64, over resistor 65 of 1.8 megohms, point 66, resistor 67 of 1.6 megohms, point 68, resistor 69 of 15,000 ohms, point 61, and resistor 70 of 22,000 ohms to ground. Point 68 in this circuit is coupled to ground over a capacitor 71 of 1,000 micro-microfarads. When conduction occurs in the "start" tube, its cathode 60 will also be conductively coupled to the anode 45, and its potential will change from slightly negative to positive with respect to ground.

The auxiliary or shield grid 72 of the "start" tube is connected to the cathode 60 and will have the same potentials as the cathode.

The "start" tube is the first tube in the chain and is followed by the "9," "8," "7," "6," "5," "4," "3," "2," and "1" priming tubes in that order. The circuits for the various priming tubes are similar and will be clear from an explanation of the circuits for the "9" priming tube (Fig. 1-A).

The anode 75 of the "9" priming tube is connected directly to the anode potential supply conductor 46.

The auxiliary or shield grid 76 of the "9" priming tube is connected over resistor 77 of 47,000 ohms, point 78, and resistor 79, of 1 megohm, to negative potential supply conductor 80, which is connected to terminal 53 and has a potential of -30 volts applied thereto. The auxiliary grid 76 is also coupled over point 78 and capacitor 74 of 10 micro-microfarads to a driving impulse input conductor 73, which connects over point 41 to point 39 in the cathode circuit for tube 32 and receives a positive driving impulse of about 150 volts each time tube 32 conducts momentarily.

The control grid 81 of the "9" priming tube is connected to point 66 in the cathode potential supply circuit for the "start" tube and, with the "start" tube non-conducting, has a normal

negative bias sufficient to prevent the "9" priming tube from becoming conducting even though driving impulses are applied to the auxiliary grid. When the "start" tube has been fired and is conducting, the positive potential of its cathode 60 will be reflected on the potential of the control grid 81 of the "9" priming tube and will reduce the negative bias thereon to a point where the tube can become conducting in response to a driving impulse impressed on its auxiliary grid.

The cathode 82 of the "9" priming tube is supplied with potential from a resistance-capacitance network, like the one for the "start" tube, which extends to ground from the negative potential supply conductor 63.

Each of the priming tubes for the digits "8" to "1" inclusive has an anode potential supply circuit and a cathode potential supply circuit like those for the "9" priming tube, each has a negative potential supply circuit for its auxiliary or shield grid and capacitance coupling from its auxiliary grid to the driving impulse input conductor 73, similar to those described above in connection with the "9" priming tube, and each has its control grid connected to the cathode potential supply circuit of the preceding tube in the chain to be primed thereby upon conduction occurring in the preceding tube.

It is to be noted that the driving impulses from tube 32 are not effective to cause an unprimed tube to conduct; consequently the impulses will be ineffective on any of the priming tubes of chain until the "start" tube has been fired and primes the "9" priming tube. The "start" tube is fired in the following manner. Point 51 in the control grid circuit for the "start" tube is coupled over conductor 85, capacitor 83 of 10 micro-microfarads, and point 87 to the motor bar or start key switch 88, which is normally open but which can be closed to connect point 87 to conductor 89, which extends to terminal 90, to which a potential of +250 volts is applied. When the motor bar or start key switch 88 is closed and the +250 volts is applied to capacitor 85, a positive impulse will be impressed on the control grid 49, which impulse is sufficient to fire the "start" tube, thereby priming or conditioning the "9" priming tube so that it can respond and be fired by the next driving impulse on conductor 73. Point 87 in the motor bar or start key control circuit is connected to ground over resistor 95 of 47,000 ohms to provide a discharge path through which capacitor 85 can be discharged when the motor bar or start key switch 88 is opened.

Each of the priming tubes, when fired, will prime the next tube of the chain, so that it will be fired by the next driving impulse. Accordingly, after the "start" tube has been fired by the closing of the start key switch 88, the next nine driving impulses will fire the tubes of the priming chain one after another.

The tubes of the chain, being gas tubes, will remain conducting, once they are fired, until they are extinguished by the operation of an extinguishing means which includes the tube 43. This operation of the extinguishing means takes place after the last tube in the chain has been fired and has effected its control, at which time all the tubes of the chain are rendered non-conducting.

Since the priming tubes of the chain are fired in sequence by successive driving impulses and are all extinguished at the same time, the several tubes will be conducting for progressively longer periods of time; that is, the "9" priming

tube will be conducting longer than the "8" tube, the "8" tube will be conducting longer than the "7" tube, etc.

Each priming tube controls a related impulse-train-producing tube by priming that tube as long as the priming tube is conducting, and enables the driving impulses from tube 32, which are impressed continuously on the impulse-train-producing tubes, to become effective to operate the tube and produce a train of impulses corresponding in number to the digit to which the priming tube is related. For example, the impulse-train-producing tube related to the "9" priming tube will produce a train containing nine impulses, the impulse-train-producing tube which is related to the "8" priming tube will produce a train of eight impulses, etc., the impulse-train-producing tube related to the "1" priming tube producing one impulse.

The circuits and controls for the impulse-train-producing tubes are similar, and it is believed that an understanding of the operation of all these tubes will be clear from a description of the operation of one of them.

The impulse-train-producing tube for producing a train of nine impulses is representative and is shown at 100 in Fig. 1-A. This tube is shown as a separate triode, but preferably it is one half of a twin triode, such as the above-mentioned 2C51 type of tube. The tube has its anode 101 connected directly to conductor 109, which, as explained earlier herein, has a potential of +250 volts applied thereto at terminal 20. The cathode 102 of the tube is connected over point 103 and resistor 104 of 2,200 ohms to point 105 on potential supply conductor 106, which has a potential of +130 volts applied thereto at terminal 107. This anode-cathode potential supply circuit has a very low impedance and will produce a strong positive impulse of about 55 volts at point 103 each time the tube 100 is operated.

Control grid 109 of tube 100 is connected over point 110 and resistor 111 of 100,000 ohms to point 112 in the cathode potential supply circuit for the "9" priming tube. Point 110 in the grid circuit is also coupled over a capacitor 113 of 250 micro-microfarads to the driving impulse input conductor 114, which is connected over point 41 to point 39 in the circuit of the driving impulse generating tube 32. When the "9" priming tube is not conducting, point 112 in its cathode circuit and consequently grid 109 of the impulse-train-producing tube 100 will be slightly negative with respect to ground, and, since the cathode 102 is at a potential of +130 volts, the tube 100 will be biased sufficiently past cut-off that the driving impulses on conductor 114 will be ineffective to cause conduction in tube 100. However, when the "9" priming tube is conducting and its cathode has become positive, point 112 will become more positive and reduce the bias on tube 100 to a point where the driving impulses on conductor 114 will be effective to cause momentary conduction in the tube 100 and thereby provide positive impulses at point 103. Capacitor 115, which is similar to capacitor 11 in the cathode circuit of the "start" tube, delays the application of the priming potential to grid 109 sufficiently that the impulse which fires the "9" priming tube will have passed before the tube 100 is ready for operation. The first driving impulse that will be effective on tube 100 will be the same one that fires the "8" priming tube.

Conductor 120 is connected to point 103 and will have the positive impulses at point 103 im-

pressed thereon. Switch 121, which can be closed by a "9" digit key or any other switch-operating device in the units denominational order, will connect the conductor 120 to a units denominational output conductor 122. Similarly, a switch 123 can be closed by a "9" digit or other switch-operating device in the tens denominational order to connect the conductor 120 to a tens denominational output conductor 124. While only two sets of switches and two denominational output conductors have been shown, it is obvious that as many can be provided as are needed according to the denominational capacity desired.

Each of the other impulse-train-producing tubes has connections similar to the ones given above and is capable of producing the required number of impulses which can be switched to output conductors 122 and 124 as desired. The use of the low impedance source of impulses allows the impulses to be switched to a plurality of output conductors without impairing the ability of the impulses to operate the accumulator.

The driving impulse, which follows the driving impulse which fires the "1" priming tube, will be effective on the primed impulse-train-producing tubes to cause the last impulse in each train to be generated and will be effective on the primed tube 144 (Fig. 1-B) to cause that tube to operate and generate the impulse for effecting an entry of the digit "1" in the accumulator. This impulse which is generated by the tube 144 goes out over conductor 145, from which it can be switched to output conductors, as 122 and 124. The impulse on conductor 145 also is used to operate the extinguishing means to cause the tubes of the chain to be extinguished and remove the priming from the impulse-train-producing tubes.

As explained earlier herein, the anodes of the "start" tube and the priming tubes "1" to "9" are connected to conductor 46. The potential of conductor 46 is derived from an impedance network having one branch which extends from point 150 on -108-volt conductor 63, over resistor 151 of 56,000 ohms, point 152, and to ground over resistor 153 of 500,000 ohms, and having another branch which extends from point 152, over point 47, to the cathode 154 of the extinguishing tube 48, and through the tube whose anode 155 is directly connected to conductor 89, to which a potential of +250 volts is applied. Tube 48 is preferably of the type sold by Radio Corporation of America under the type designation 6AQ5, and, by varying the impedance thereof, the potential applied to conductor 46 and the anodes of the tubes of the chain can be controlled.

Normally, the potential on the control grid 156 of tube 48 is such that the tube will conduct sufficiently to give its cathode 154 and the conductor 46 a potential of +125 volts. However, when the potential on the grid 156 of tube 48 is modified to increase the impedance of the tube so that less current flows therethrough, the cathode potential and that of conductor 46 will become less positive and even may become negative with respect to ground, thereby causing the anode potential of the conducting tubes of the chain to drop below their cathode potential and the tubes to be extinguished.

The potential of grid 156 is controlled from a resistor 158 in the anode circuit of a twin triode control tube 161, which is preferably of the type sold by Radio Corporation of America under the type designation 12AX7. The anodes 162 and 163 are connected together and over the resistor

160 of 470,000 ohms to conductor 89, to which a potential of +250 volts is applied.

The cathode 164 of one of the triodes of tube 161 is connected directly to terminal 165 and has a potential of +65 volts applied thereto. The cathode 165 of the other triode of tube 161 is connected directly to terminal 167, to which a potential of -98 volts is applied.

Grid 170 cooperates with the anode 163 and the cathode 164 to determine the normal potential applied to grid 156 of tube 48. Grid 170 is supplied with the required potential from an adjustable tap 171 on resistor 153.

Grid 172 cooperates with the anode 162 and the cathode 166 of tube 161 and is effective therethrough to modify the potential of grid 156 of extinguishing tube 48 to increase the impedance of this tube and cause the extinguishing of the tubes of the chain.

The impulse which is generated by tube 144 and is applied to conductor 145 is impressed on grid 172, either directly or through an impulse-widening device, and will cause the extinguishing of the tubes of the chain. In the disclosed embodiment, the impulse on conductor 145 will be applied through an impulse-widening device. Conductor 145 is coupled through a capacitor 175 of .005 microfarad to the anode 176 of a diode 177. Preferably this diode is one half of a twin diode tube of the type sold by Radio Corporation of America under the type designation 6AL5. Anode 176 of the diode 177 is also connected over resistor 178 of 39,000 ohms and conductor 179 to conductor 63, which has a potential of -108 volts applied thereto. Cathode 180 of the diode is also connected to conductor 179 over a resistor 181 of 1 megohm in parallel with a capacitor 182 of 250 micro-microfarads. Point 183 in this circuit is connected over resistor 184 of 200,000 ohms to the grid 172 of the control tube.

A positive impulse on conductor 145 will be effective, through the low impedance of the diode 177, to charge capacitor 182 and make point 183 and the grid 172 connected thereto more positive. Since the discharge paths for the capacitor 182 are through the resistor 181 of 1 megohm and the high back impedance of the diode 177, the grid 172 will remain positive for a longer time than that required for the impulse on conductor 145.

When grid 172 becomes more positive and more current flows through resistor 160, grid 156 will become more negative and increase the impedance of tube 48, thereby to reduce the anode potential applied to the tubes of the chain sufficiently to cause them to be extinguished.

The impulse-widening means, while not necessary, provides an additional factor of safety in the operation of the device, because it allows the anode potential for the tubes of the chain to be depressed for a longer period of time than required to deionize them and insures that all tubes of the chain will be extinguished.

Accordingly, for each operation of the "start" tube, impulse-train-producing tube 169 will produce a train of nine impulses on conductor 126; tube 128 will produce a train of eight impulses on conductor 121; tube 122 will produce a train of seven impulses on conductor 123; tube 134 will produce a train of six impulses on conductor 135; tube 136 will produce a train of five impulses on conductor 137; tube 138 will produce a train of four impulses on conductor 139; tube 140 will produce a train of three impulses on conductor 141; tube 142 will produce a train of two impulses on conductor 143; and tube 144 will produce an

impulse on conductor 145. Each impulse train is common to the plurality of denominational output conductors, and the trains of impulses can be switched to the output conductors according to the digits desired to be entered into the various denominations of the accumulator.

If no entry is to be made in any denominational order of the accumulator, a zero switch, as 146, for that order is closed to connect the related output conductor to conductor 106 over a resistor 147 of 2,200 ohms to provide a comparable low impedance loading for the output conductor when it is not otherwise connected to an impulse-train-producing tube.

It should be noted that the "start" tube and its controls will allow only one impulse-train-producing operation of tubes 100, 130, 132, 134, etc., for each closure of the motor bar or key switch 88, because, as long as the switch remains closed, capacitor 86 will remain charged, and no additional firing impulses can be applied to the control grid 49 of the "start" tube.

The impulse generator also includes a transfer-effecting impulse-generating means which is controlled from the oscillator and is timed to cause transfer entries to be made without interference with digit entries in the accumulator.

The transfer-effecting impulse-generating tube 190 (Fig. 1-A), which preferably is one half of the above-noted 12AU7 type of tube, has its anode 191 connected over point 192 and resistor 193 of 22,000 ohms to conductor 19, to which is applied a potential of +250 volts, and has its cathode 194 directly connected to ground. Control grid 195 normally biases the tube to cut-off by being connected over resistor 196, point 197, and resistor 198 to conductor 35, to which a potential of -30 volts is applied at terminal 36. Control grid 195 is also coupled from point 197 over capacitor 199 of 250 micro-microfarads to point 15 in the anode circuit of tube 11 of the oscillator, and will allow the tube 190 to conduct each time the potential of point 15 becomes more positive in the operation of the oscillator.

Whenever the tube 190 conducts, a negative potential drop of about 150 volts occurs at point 192 in its anode circuit, and these potential drops are applied over conductor 200 (Figs. 1-A and 1-B) and resistor 201 of 47,000 ohms to the transfer means of the units denominational order of the accumulator and over resistor 202 of 47,000 ohms to the transfer means of the tens denominational order of the accumulator. The negative impulses which are impressed on conductor 200

will occur during the intervals between the positive impulses on the denominational output conductors 122 and 124 and are effective to cause transfer entries to be made in the accumulator without interfering with the digit entries. The manner in which the transfer-effecting impulses cause the operation of the tens transfer means will be explained more fully hereinafter.

Accumulator

65 Two denominational orders of the accumulator are shown in Figs. 2 and 3.

Each denominational order includes an electronic coupling device, an electronic tens transfer means, and a plurality of interrelated electronic devices capable of accumulating in the decimal notation and representing, in combinational form, the units digit of said accumulation.

Fig. 2 shows the units denominational order of the accumulator.

The coupling device is shown as a twin triode,

tube 220, preferably of the above-noted 2C51, type, though, as will appear later, only one of the triodes is utilized in the units order, the one for coupling the order of the accumulator to the corresponding denominational output conductor of the impulse generator. In the embodiment shown, there are no tens transfer entries to be made in the units denominational order of the accumulator, and accordingly the other of the triodes is not used to control entries therein.

Tube 220 has both of its anodes 221 and 222 connected together and over point 223 and resistor 224 of 47,000 ohms to conductor 225, to which a potential of +250 volts is applied at terminal 226, and has its cathodes 227 and 228 and shield 219 grounded.

Grids 230 and 231 have biasing potential supplied thereto from a biasing potential supply circuit which extends to ground from conductor 232, to which a potential of -75 volts is applied at terminal 233, over resistor 234 of 100,000 ohms and resistor 235 of 47,000 ohms, grid 230 being connected over point 236, and resistor 237 of 47,000 ohms to point 238 in the bias potential supply circuit and grid 231 being likewise connected over a resistor 240 of 47,000 ohms to point 241 in the bias potential supply circuit. Point 241 is connected to ground over a stabilizing capacitor 242 of 500 micro-microfarads. The potential supplied to the grids normally biases both halves of the tube to cut-off.

The units denominational output conductor 122 (Figs. 1-A, 1-B, and 2) of the impulse generator is coupled over capacitor 243 of 250 micro-microfarads to grid 230, which controls conduction between anode 221 and cathode 227 of the left triode in the tube 220. Whenever an impulse of an impulse train is impressed on conductor 122, it will be effective to cause the triode, which is controlled by grid 230, to conduct and produce a potential drop at point 223 due to resistor 224 in its anode circuit.

In the units denominational output conductor 122 of the disclosed embodiment of the accumulator, grid 231, which controls the right-hand triode of the tube 220, will have no impulses applied thereto, so this triode of the tube will remain biased to cut-off.

The potential drops which are produced at point 223 when conduction occurs in the tube are used to provide negative impulses to operate the interrelated devices of this denominational order for accumulating amounts. The interrelated devices consist of four trigger pairs connected in cascade and with selective feed-back circuits to enable them to accumulate values in the decimal notation and to represent the various digits of the notation by different combinations of "on" or "off" conditions of the trigger pairs.

As is well known, an electronic device known as a trigger pair consists of a pair of electron discharge tubes having interconnections therebetween to control their operation so that, at any given time, one of the tubes is conducting and the other tube is non-conducting, and the act of changing the conducting condition of one of the tubes will cause the conducting condition of the other of the tubes of the pair to change. With the circuit constants to be given herein, the trigger pairs will be relatively insensitive to positive impulses but will respond to negative impulses, so that a negative input impulse applied commonly to the tubes of the pair will cause reversal of the conducting and non-conducting condition of the tubes. The trigger pair

may be made up of two separate tubes; however, in order to provide a more compact device, each of the cascaded trigger pairs in the disclosed embodiment of the invention is formed by interconnecting the two halves of a twin triode type of tube, preferably of the aforementioned 2C51 type.

The first trigger pair of the cascade will be that marked A, the second trigger pair will be B, the third trigger pair will be C, and the fourth and final trigger pair of the cascade will be D. The trigger pairs will be considered in their "on" condition when the left triode of the trigger pair is conducting and in their "off" condition when the left triode of the trigger pair is in non-conducting condition. The manner in which the trigger pairs represent the various digits can be seen from the following table, in which "O" designates the "off" condition and "X" designates the "on" condition of a trigger pair.

Digit	A	B	C	D
0.....	O	X	O	O
1.....	X	X	O	O
2.....	O	O	X	O
3.....	X	O	X	O
4.....	O	X	X	O
5.....	X	X	X	O
6.....	O	O	X	X
7.....	X	O	X	X
8.....	O	X	X	X
9.....	X	X	X	X

Trigger pair A is the first trigger pair of the cascade and is operated by impulses impressed thereon from the coupling device, tube 220. The left triode 245 of the trigger pair has its anode 246 connected over resistor 247 of 47,000 ohms to the +250-volt conductor 225 and has its cathode 248 connected directly to ground. Similarly, the right triode 250 of the trigger pair has its anode 251 connected over resistor 252 of 47,000 ohms to the +250-volt conductor 225 and has its cathode 253 directly connected to ground.

Grid 255 of the left triode 245 is connected to a negative bias supply over point 256, resistor 257 of 150,000 ohms, and conductor 232, to which a potential of -75 volts is applied at terminal 233, and also is coupled to the anode 251 of the right triode 250 over a network containing resistor 258 of 200,000 ohms shunted by resistor 259 of 100 ohms in series with capacitor 260 of 150 micro-microfarads. In a similar manner, the grid 263 of the right triode 250 is connected to the negative bias supply over point 264 and resistor 265 of 150,000 ohms to conductor 266, which is connected over a reset switch 267 to conductor 232. Grid 263 is also coupled to the anode 246 of the left triode 245 over a network containing resistor 268 of 200,000 ohms shunted by resistor 269 of 100 ohms in series with capacitor 270 of 150 micro-microfarads.

Points 256 and 264 in the bias supply circuits for the grids 255 and 263 are coupled, respectively, over capacitors 275 and 276 of 25 micro-microfarads to a conductor 277, thence over resistor 278 of 47,000 ohms to the point 223 in the anode circuit of the coupling device, tube 220.

With the circuit constants given, trigger pair A will be responsive to negative impulses and will reverse the conducting status of the triodes therein each time a negative impulse is impressed on the grids of the triodes. Accordingly, the trigger pair will reverse its conducting status each time the coupling device responds to an impulse from the impulse generator and sends a negative impulse to the pair.

Trigger pair B, which is the second trigger pair of the cascade, is operated to reverse the conductive condition of the triodes therein in response to an impulse impressed thereon from trigger pair A when that pair goes from its "on" condition to its "off" condition. Trigger pair B is also operated from its "off" condition to its "on" condition in response to a feed-back impulse from trigger pair D in a manner to be explained more fully hereinafter. The anodes 280 and 281, respectively, of the left triode 282 and the right triode 283 of this pair are connected over resistors 284, and 285 of 47,000 ohms, respectively, to the +250-volt conductor 225, and the cathodes are connected to ground.

Grid 286 of the left triode 282 is connected to negative bias supply by being connected over point 287 and resistor 288 of 150,000 ohms to conductor 286, and is also coupled to the anode 281 of the right triode 283 over a network containing resistor 293 of 200,000 ohms shunted by resistor 291 of 100 ohms in series with capacitor 292 of 250 micro-microfarads. Grid 295 of the right triode 283 is connected to the negative bias supply over resistor 296 of 47,000 ohms, point 297, resistor 298, of 150,000 ohms, and conductor 266. Grid 295 is also coupled to the anode 280 of the left triode 282 over resistor 299 and resistor 300 of 200,000 ohms, resistor 299 being shunted by resistor 300 of 100 ohms in series with a capacitor 301 of 250 micro-microfarads.

Point 287 in the bias supply circuit to grid 286 is connected over resistor 304 of 47,000 ohms and capacitor 305 of 25 micro-microfarads to conductor 306, which extends to the anode 251 of the right triode 250 of trigger pair A. Point 297 in the bias supply circuit for grid 295 is also coupled to conductor 306 over a capacitor 307 of 25 micro-microfarads. Each time trigger pair A is operated to its "off" condition and the right triode 250 thereof conducts, a negative impulse will be sent over capacitors 304 and 307 to the grids 286 and 295 of the trigger pair B to cause a reversal of the conducting condition of the triodes therein.

Resistors 293 and 304 are isolation resistors, which are operative to control the effect of the feed-back impulse on trigger pair B and also cooperate with the rectifier in the feed-back circuit to enable rectifiers of the semi-conductor or barrier-layer type having lower back impedance to be used and still prevent impulses from trigger pair B from causing improper operation of trigger pair D. The manner in which these resistors are operable to perform the above functions will be explained more fully hereinafter, when the feed-back circuit and its operation are explained.

Trigger pair C, which is the third trigger pair of the cascade, is operated to reverse the conducting condition of the triodes therein in response to an impulse from trigger pair B when that pair goes from its "on" condition to its "off" condition. Trigger pair C is also operated from its "off" condition to its "on" condition in response to a feed-back impulse from trigger pair D in a manner to be explained more fully hereinafter. The circuit arrangement and circuit constants for trigger pair C are identical with those of trigger pair B and will not be repeated.

Trigger pair D, which is the last trigger pair in the cascade, is operated by impulses impressed thereon from trigger pair C and is effective to send feed-back impulses selectively to trigger

pairs B and C and to send an impulse to a tens transfer means to prepare it for a tens transfer operation.

The left triode 310 of trigger pair D has its anode 311 connected over point 312, resistor 313 of 22,000 ohms, point 314, and resistor 315 of 22,000 ohms to the +250-volt conductor 225 and has its cathode connected to ground. In a like manner, the right triode 316 has its anode 317 connected over point 318, resistor 319 of 22,000 ohms, point 320, and resistor 321 of 22,000 ohms to the +250-volt conductor 225, and has its cathode connected to ground.

Grid 325 of the left triode 310 is connected to the negative bias supply over point 326, resistor 327 of 150,000 ohms, and conductor 286, and is also coupled to the anode 317 of the right triode 316 over resistor 328 of 200,000 ohms, shunted by resistor 329 of 100 ohms in series with capacitor 330 of 250 micro-microfarads. Similarly, the grid 335 of the right triode 316 is connected to the negative bias supply over point 336, resistor 337 of 150,000 ohms, and conductor 266. Grid 335 is also coupled to the anode 311 of the left triode 310 over resistor 338 of 200,000 ohms, shunted by resistor 339 of 100 ohms in series with capacitor 340 of 250 micro-microfarads.

Points 326 and 336 in the bias potential supply circuits of grids 325 and 335, respectively, are coupled over capacitors 341 and 342 of 25 micro-microfarads to conductor 343, which extends to the anode of the right triode of trigger pair C and enables a negative impulse to be impressed on the grids 325 and 335 each time trigger pair C turns from its "on" condition to its "off" condition.

A feed-back circuit extends from point 320 in the anode circuit for the right triode 316 of trigger pair D, over capacitor 345 of 150 micro-microfarads, point 346, rectifier 347, which is, for example, a germanium crystal diode of the type sold by Western Electric Company under the type designation WE400B, and conductor 348 to the grid 295 of the right triode 283 of the trigger pair B. The rectifier 347 is oriented to pass negative feed-back pulses from the trigger pair D to the trigger pair B and to prevent negative impulses on grid 295 from being transmitted to trigger pair D. Point 346 in the feed-back circuit is connected to ground over a resistor 349 of 470,000 ohms to provide a leakage path to discharge capacitor 345.

The above feed-back circuit and its related circuits cooperate in the following manner to make it possible to use crystal diodes instead of vacuum tube diodes in the feed-back circuit. In the circuit arrangement shown, the feed-back impulse is applied directly to grid 295, and the isolation resistors 293 and 304 are in series between the feed-back circuit and grid 286 of the left triode 282. These resistors reduce materially the effect of the negative feed-back impulse on grid 286 and the triode 282 controlled thereby. By thus attenuating the effect of the feed-back impulse on the left triode, the effect of the potential change of anode 281 will be greater and a smaller-amplitude feed-back impulse applied directly to the grid 295 of the right triode will be as effective to reverse the operation of the pair as the larger-amplitude impulse applied in common to the triodes of the pair from the preceding trigger pair of the cascade. This enables the feed-back impulse to be taken from the midpoint of the resistance in the anode circuit for the right triode 316 of trigger pair D, at point 320, instead of

directly from the anode at point 318. With the feed-back impulse taken from point 329 by connecting the feed-back circuit thereto, resistor 319 is placed in series between the feed-back circuit and the anode 317 of the triode 316 and attenuates the effect on anode 317 and grid 325, coupled thereto, of any impulses transmitted from trigger pair B. Similarly, resistor 296 in the circuit to grid 295 of the right triode of trigger pair B will attenuate impulses applied to the grid 295 from anode 280 of the left triode 282 of trigger pair B, and also from anode 251 of right triode 250 of trigger pair A, and, consequently, will attenuate the effect of impulses from these sources on the feed-back circuit, which is connected directly to grid 295. The above attenuating effects of resistors 296 and 319 are cumulative and are effective in the circuit arrangement to enable crystal rectifiers of the semi-conductor or barrier-layer type, which can be much smaller but which have lower back resistance than vacuum tube rectifiers, to be used in the feed-back circuit without causing improper operations to take place.

A similar feed-back circuit extends from the midpoint 314 of the anode resistance network for the left triode 310 of trigger pair D, over capacitor 355 and rectifiers 356, to the grid of the right triode of trigger pair C, and enables the turning of trigger pair D "on" to send a negative feed-back impulse to trigger pair C to turn it from "off" to "on."

The manner in which the various trigger pairs are operated in combinations to represent digits of the decimal notation will now be explained in an operation in which ten impulses are sent to the denomination to operate it through a complete cycle and return it to starting condition. As shown in the tabulation given earlier herein, the zero or starting condition of the trigger pairs of the denomination is that in which trigger pairs A, C, and D are in "off" condition, with their right triodes conducting, and trigger pair B is in its "on" condition, with its left triode conducting. All input impulses to the denomination are applied to the coupling device, tube 220, which in turn applies them to trigger pair A, the first trigger pair of the cascade.

The first impulse applied to trigger pair A changes it from its "off" condition to its "on" condition, so that the trigger pairs A and B will be "on" and trigger pairs C and D will be "off" to represent the digit "1."

The second impulse applied to trigger pair A changes it from "on" to "off." As trigger pair A goes from "on" to "off," it sends an impulse to trigger pair B, which turns trigger pair B from "on" to "off," and trigger pair B, in going from "on" to "off," sends an impulse to trigger pair C to turn it from "off" to "on." At the end of this entry, trigger pairs A, B, and D are "off," and trigger pair C is "on," to represent the digit "2."

The third impulse applied to trigger pair A merely changes that pair from "off" to "on." At the end of this entry, trigger pairs A and C are "on" and trigger pairs B and D are "off" to represent the digit "3."

The fourth impulse applied to trigger pair A turns trigger pair A from "on" to "off," and trigger pair A, in turning "off," sends an impulse to trigger pair B to turn it from "off" to "on." At the end of this entry, trigger pairs A and D are "off" and trigger pairs B and C are "on" to represent the digit "4."

The fifth impulse applied to trigger pair A merely turns this trigger pair from "off" to "on," and, at the end of this entry, trigger pairs A, B, and C will be "on" and trigger pair D will be "off" to represent the digit "5."

The sixth impulse applied to trigger pair A will turn this trigger pair from "on" to "off," and, in turning from "on" to "off," trigger pair A will send an impulse to trigger pair B to turn it from "on" to "off." The turning of trigger pair B to "off" will send an impulse to trigger pair C to turn it from "on" to "off," and trigger pair C, in turning to "off," will in turn send an impulse to trigger pair D to turn it from "off" to "on." When the trigger pair D is turned from "off" to "on," a feed-back impulse is sent from the left triode of trigger pair D to the right triode of trigger pair C to cause trigger pair C to be turned "on." At the end of this operation, trigger pairs A and B will be "off," and trigger pairs C and D will be "on" to represent the digit "6."

The seventh impulse applied to trigger pair A will merely turn trigger pair A from "off" to "on," and, at the end of this entry, trigger pairs A, C, and D will be "on" and trigger pair B will be "off" to represent the digit "7."

The eighth impulse applied to trigger pair A will turn trigger pair A from "on" to "off," and the turning of trigger pair A "off" sends an impulse to trigger pair B to turn trigger pair B from "off" to "on." At the end of this entry, trigger pairs B, C, and D will be "on," and trigger pair A will be "off," to represent the digit "8."

The ninth impulse applied to trigger pair A will merely turn trigger pair A from "off" to "on," so that, at the end of this entry, all the trigger pairs will be "on" to represent the digit "9."

The tenth impulse which is applied to trigger pair A will turn trigger pair A from its "on" condition to its "off" condition, and trigger pair A, in turning to its "off" condition, will send an impulse to trigger pair B to turn it from "on" to "off." Trigger pair B, in turning to its "off" condition, will send an impulse to trigger pair C to turn it from "on" to "off," and trigger pair C, in turning "off," will send an impulse to trigger pair D to turn it from "on" to "off." As trigger pair D is turned from "on" to "off," the other feed-back circuit becomes effective, and an impulse is sent from the right triode 316 thereof to the grid 295 of the right triode of trigger pair B to turn the trigger pair B from "off" to "on." At the end of this entry, the trigger pairs A, C, and D will be in "off" condition, and trigger pair B will be in "on" condition, which is the condition in which they were at the beginning of the entry of the ten impulses.

It is seen, therefore, that the cascaded trigger pairs of the denomination can be operated in combinations of "on" and "off" conditions to represent the digits "1" to "9" and "0," and can be returned to starting condition upon the application of ten impulses to the first trigger pair of the cascade.

Fig. 3 shows the coupling device, the cascaded trigger pairs A, B, C, and D, and the tens transfer means of the tens denominational order of the accumulator. The tens denominational order is representative of all intermediate orders of the accumulator. The highest denominational order of the accumulator would be the same as the intermediate orders except that it would not be required to control a transfer means to transfer values to a higher order. Except for an additional control of the coupling device by which

tens transfer entries can be made from a lower order, the circuits of this figure are the same as those for the units denominational order shown in Fig. 2. Where the circuit constants and circuits of Fig. 3 are the same as those of Fig. 2, the description of them will not be repeated.

The coupling device for the tens denominational order is a twin triode 360 (Fig. 3), similar to the twin triode 220 (Fig. 2). As is the case with the coupling device in Fig. 2, the anodes 361 and 362 (Fig. 3) are connected together and over a resistor 363 of 47,000 ohms to a +250-volt conductor 364, and the cathodes are connected to ground. Grid 365 of the left triode is supplied with negative grid bias from conductor 366, to which -75 volts is applied, and is coupled over capacitor 367, of 250 micro-microfarads, to the tens denominational output conductor 124 of the impulse generator (Figs. 1 and 1-A). The left triode is normally biased to cut-off but will conduct momentarily when the positive output impulses from the impulse generator are applied to grid 365. Each time this triode conducts, the drop across the anode resistor 363 will cause a negative impulse to be applied to the first trigger pair of the cascade to cause an advance in the digit represented by the operating condition of the cascaded trigger pairs.

Grid 370 of the right triode of the coupling device is supplied with negative biasing potential from conductor 366 and is coupled over capacitor 371, of 250 micro-microfarads, to conductor 372, which extends to the transfer means of the next lower order and receives a positive impulse each time a transfer entry is made from the lower order. Each positive transfer impulse which is applied to grid 370 will cause the right triode of the coupling device to conduct momentarily, which conduction will produce a drop across the anode resistor 363 similar to the one produced by an impulse from the impulse generator. This drop is applied as a negative impulse to the first trigger pair of the cascade to cause a unit advance in the digit representation of the cascaded trigger pairs.

Tens transfer means

Tens transfer means are provided for the accumulator to make an entry of a value of "one" in the next higher order of the accumulator each time an order exceeds its capacity. Since the same type of transfer means couples adjacent denominational orders of the accumulator, the operation of the various transfer means will be clear from a description of the operation of the means coupling the units and tens denominational orders of the accumulator.

The transfer means includes a trigger pair which is operated from a normal conducting condition when the related denominational cascaded trigger pairs exceed their digital capacity and is effective to cause an entry in the next higher order when restored to normal condition.

The tens transfer trigger pair (Fig. 2) is shown as being made up of two halves of a twin triode, tube 375, preferably of the above-mentioned 2C51 type.

Anodes 376 and 377 of the left and right triodes of this trigger pair are connected, respectively, over resistors 378 and 379 of 47,000 ohms to the +250-volt conductor 225, and the cathodes of these triodes are connected to ground.

Grid 380 of the left triode is coupled to the negative bias supply conductor 232 over point

381 and resistor 382 of 150,000 ohms and also is coupled to anode 377 of the right triode by the trigger connection including resistor 383 of 200,000 ohms, shunted by resistor 384 of 100 ohms in series with capacitor 385 of 250 micro-microfarads. In a corresponding manner, grid 386 of the right triode is coupled to the negative bias supply conductor 266 over point 394 and resistor 387 of 150,000 ohms and also is coupled to anode 376 of the left triode by the trigger connection including resistor 388 of 200,000 ohms, shunted by resistor 389 of 100 ohms in series with capacitor 390 of 250 micro-microfarads.

When the accumulator is initially set in operation or is reset to zero, the tens transfer trigger pair is set in its normal condition, with the right triode conducting, as will be explained more fully hereinafter when the resetting operation is considered.

When a tens transfer is required, the cascaded trigger pairs of the denomination will cause the tens transfer trigger pair to operate to reverse its conducting status. This is accomplished in the following manner. As is seen from the tabulation given earlier herein, the trigger pair D will change from its "on" condition to its "off" condition only when the digit represented by the cascaded trigger pairs changes from "9" to "0."

The drop across anode resistors 318 and 321 of the right triode of this trigger pair which occurs when the pair changes from "on" to "off" is applied as a negative impulse to grid 386 of the right triode of the tens transfer trigger pair, over conductor 391, resistor 392 of 47,000 ohms, capacitor 393 of 25 micro-microfarads, and point 394, and will cause the tens transfer trigger pair to be operated from its normal condition and reverse the conducting status of its triodes.

As explained earlier herein in connection with the impulse generator, the transfer-effecting impulse-generating tube 190 (Fig. 1-A) is driven from the oscillator and produces negative potential drops which are transmitted over conductor 200 and resistors, as 201 and 202, during the intervals between the occurrence of positive impulses on the denominational output conductors, as 122 and 124.

The drop transmitted over resistor 201 is transmitted further over conductor 395 (Figs. 1-B and 2), capacitor 396 of 25 micro-microfarads, and point 381 and is impressed as a negative impulse on grid 380 of the left triode to cause the trigger pair to reverse its conducting status and return to its normal condition if it had been operated from normal condition by a required tens transfer.

If the tens transfer trigger pair is in its normal condition, the left triode will already be in non-conducting condition, and the negative transfer-effecting impulses applied to grid 380 will not have any effect on the trigger pair to change the status of conduction of its triodes; but, if the trigger pair has been changed from normal condition due to a required tens carry, then the left triode will be conducting and the negative transfer-effecting impulse will render the left triode non-conducting, and, through the trigger action, will restore the pair to its normal condition. As the left triode becomes non-conducting, its anode potential becomes more positive, and this potential change is transmitted over conductor 400, resistor 401 of 47,000 ohms, conductor 372 (Figs. 2 and 3), and capacitor 371 to the grid 370 in the right triode of the coupling device, tube 360, of the tens denominational order to

cause an impulse to be impressed on the cascaded trigger pairs of the tens denominational order to make a unit entry therein.

It is to be noted that, since the transfer entries are effected by impulses which are generated in the intervals between the times when digit-entry-effecting impulses can be generated, transfer entries can be made at any time during or after a digit entry without interfering with the digit entry.

The tens transfer means, which is controlled from the tens denominational order trigger pair D (Fig. 3), includes the twin triode 402, which has transfer-effecting impulses applied thereto from the impulse generator over conductor 200, resistor 202, conductor 403 (Figs. 1-B and 3), and capacitor 404, and which can send a tens transfer signal over resistor 405 and conductor 406 to the next higher or hundreds order of the accumulator when required.

In a similar manner, other transfer means can be controlled from the trigger pairs D of their related orders and can be operated by transfer-effecting impulses to cause tens transfer entries to be made in appropriate higher orders.

Resetting

In order to prepare the accumulator initially to receive entries or to reset it to its zero condition, reset switches, as 267 in Fig. 2 and 410 in Fig. 3, are provided in the negative bias supply circuits for the grids of the right triodes of trigger pairs A, C, and D and the left triode of trigger pair B. Momentary opening of the switches will remove negative bias potential from these grids and will cause the trigger pairs A, C, and D to be set in their "off" condition and trigger pair B to its "on" condition.

While separate reset switches as 267 and 410 are shown for various denominations, it is obvious that conductors, as 266, for the various denominations could be connected together and over a single reset switch to a source of -75 volts.

The transfer trigger pairs are also conditioned by the operation of the reset switches, which remove negative bias from the grids of the right triodes of these trigger pairs and cause these trigger pairs to be set to their normal position, with the right triode conducting. This control of the transfer trigger pairs from the reset switches insures that these trigger pairs will always be set to their normal condition initially or after a resetting operation, and prevents any improper transfers from being made as a result of changing trigger pair D to its "off" condition in the initial setting or resetting operations.

Digit-manifesting means

Means are provided to manifest the digit values represented by the combinations of "on" and "off" conditions of the cascaded trigger pairs of the various denominational orders of the accumulator.

The manifesting means for each of the denominational orders are substantially the same, that for the units denominational order including a digit-manifesting wheel 411 (Fig. 2), a read-out scanning switch 412, and a notched element 413, which can rotate together and which are driven by a friction drive, shown diagrammatically at 414, until arrested by a stop pawl 415 engaging a notch in the element 413. For convenience in illustration, a separate friction drive is shown for the manifesting means in each denominational order, but it is obvious that a com-

mon driving means which is capable of frictionally driving the manifesting means in the various denominational orders could also be used.

Pawl 415 is urged counter-clockwise (Fig. 2) about its pivot 416 by spring 417 into engaging relation with the notches in element 413 to arrest the scanning switch and the manifesting wheel 411 in any one of the positions "1" to "9" and "0" as required by the digit value represented by the related denomination of the accumulator. A magnet 420 in the anode circuit of a control triode 421, shown here as the left-hand triode of a twin triode, tube 422, of the aforementioned 2C51 type, will be energized to move the pawl 415 out of engagement with the element 413 and free the manifesting wheel 411 and the scanning switch 412 for movement whenever the control triode 421 conducts.

Control triode 421, which controls the position of the pawl 415, has its anode connected over the winding of magnet 420 to the terminal 423, to which +300 volts is applied, and has its cathode connected to ground over a resistor 424 of 3,900 ohms.

Grid 425 of triode 421 is connected to the read-out scanning switch 412 and has potential applied thereto as follows. The scanning switch 412, as it rotates, engages successively one after another of a series of contacts connected to digit-representing lines which are connected over resistors, as 426, of 2.2 megohms, to various ones of the anodes of the right and left triodes of the cascaded trigger pairs. Depending upon whether the trigger pairs are "on" or "off," the anode potentials of their left and right triodes will be either at +250 volts or at a lower potential resulting from the drop across the anode resistors of conducting triodes. The pattern of the resistance network connections for each denominational order is shown clearly in Fig. 2 and is so arranged that, for any digit represented by the combination of "off" and "on" conditions of the cascaded trigger pairs, the line corresponding to that digit will have a potential which is less positive than that of any other line. By adjusting the cathode potential of the triode 421, this least positive potential can be made to be the only one which will be effective to bias the triode 421 to cut-off, thereby de-energizing the magnet 420 and allowing the pawl 415 to engage in the notch in element 413. Accordingly, as the read-out scanning switch 412 is driven over its related contacts, it will apply their various potentials successively to the grid 425. The potentials which are more positive than the cut-off potential will not bias the triode 421 to cut-off; accordingly, the scanning switch 412 will be driven until it engages the contact having this cut-off potential applied thereto, which potential is applied to the grid 425 of the triode 421 and biases the triode to cut-off, thereby releasing the pawl 415. Pawl 415, engaging the notch in the element 413, will stop the scanning switch 412 on the contact having this cut-off potential and will stop the digit-manifesting wheel 411 with the corresponding digit in reading position, as indicated by the arrow 427, where they remain as long as cut-off potential is applied to the grid of the control triode 421.

Any further entry in the denomination will change the combination of "on" and "off" conditions of the cascaded trigger pairs and will remove the cut-off bias from the control triode 421, allowing it to conduct again. This will en-

ergize magnet 420, which moves the pawl 415 from engagement with the element 413 and frees the digit-manifesting wheel 411 and the scanning switch 412 for further movement until the scanning switch engages another contact which is at cut-off potential.

The potential of the cathode of control triode 421 is adjusted by a second triode 430, which is the right triode of the twin triode, tube 422, connected to resistor 424. The anode of this second triode 430 is connected directly to the +300-volt terminal 423, and the cathode of the second triode 430 is connected to ground over the resistor 424.

Grid 431 of triode 430 derives its potential over an adjustable tap 432 from resistor 433, which is connected between the anode potential supply conductor 225, for the cascaded trigger pairs, and ground. By adjusting the tap 432, the potential on grid 431 can be made such that conduction in triode 430 will raise the potential of the cathode of triode 421 to a value which will be less positive than all but one of the potentials, the cut-off potential, which are applied to its grid 425 from the read-out scanning switch 412.

The second triode 430 has another very important function; namely, that of serving as a compensating means in the indicator control tube circuit to compensate for variations in potential applied to the anodes of the cascaded trigger pairs. Since the potentials sensed by the read-out scanning switch 412 and applied to the grid 425 are derived from the anode potential supply for the cascaded trigger pairs over conductor 225, variations in this potential would cause variation in the grid potential and possible misoperation of the digit-manifesting means. However, since the grid 431 of the second triode 430 is also supplied, through its tap 432 to resistor 433, with potential from the anode potential supply conductor 225, variations in the anode potential supply will cause a variation in the conductivity of the second triode 430, which will provide a compensating variation in the cathode potential of triode 421 to maintain the relation between the cathode and grid potentials of this triode substantially constant despite variation in the potential supplied to the anodes of the cascaded trigger pairs.

The digit-manifesting means for the tens denominational order, as shown in Fig. 3, and for any other orders which might be provided in the accumulator, are controlled and operate in the same manner as described above.

The claims of the instant application are confined to the accumulator per se. Claims to the impulse generator are presented in a divisional application, Serial Number 215,483, and claims to the data-indicating means are presented in another divisional application, Serial Number 215,484.

While the form of the invention shown and described herein is admirably adapted to fulfill the objects primarily stated, it is to be understood that it is not intended to confine the invention to the one form or embodiment disclosed herein, for it is susceptible of embodiment of various other forms.

What is claimed is:

1. In combination, four electronic devices, each operable alternately to "on" and to "off" condition in response to impulses impressed thereon, and including means to produce potential changes each time the device changes from either condi-

tion to the other, said devices by their "on" and "off" conditions, in combination, representing the digits "1" and "9" to "0"; circuits connecting the devices in series and enabling a potential change, produced by every operation of a device to said "off" condition, to be transmitted as an impulse to the next device of the series to cause an operation thereof; means to impress input impulses on the first device of the series; a unidirectional circuit connecting the fourth electronic device in the series to the third electronic device in the series for transmitting a potential change, produced by the fourth electronic device as it is operated to "on" condition, as an impulse to the third electronic device to cause it to operate; and a second unidirectional circuit connecting the fourth electronic device of the series to the second electronic device of the series for transmitting a potential change, produced by the fourth electronic device as it is operated to "off" condition, as an impulse to the second electronic device to cause it to operate; said series connections and two unidirectional connections cooperating to enable the four electronic devices to operate to accumulate amounts in the decimal notation by causing the electronic devices, in combinations, to progressively represent the digits "1" to "9" and "0" and to return to any particular digit-representing combination after ten impulses have been applied to the input means.

2. In combination, four pairs of electron discharge devices; circuits cross-connecting each pair of devices to form a trigger pair operable alternately to "on" and to "off" condition in response to impulses and including means to produce potential changes each time the pair changes from either condition to the other, said trigger pairs, by combinations of "on" and "off" conditions, representing the digits "1" to "9" and "0"; circuits connecting said trigger pairs in cascade to transmit the potential change, produced by a trigger pair assuming its "off" condition, as an impulse to the next trigger pair of the cascade to cause it to operate and change its condition; means to preset the trigger pairs with the first, third, and fourth trigger pairs in said "off" condition and said second trigger pair in said "on" condition; an input circuit upon which input impulses are applied to the first trigger pair; a unidirectional feed-back circuit connecting one of the devices of the fourth trigger pair to the third trigger pair to enable an impulse to be sent to the third trigger pair from the fourth trigger pair each time the fourth trigger pair operates to said "on" condition; and a further unidirectional feed-back circuit connecting the other of the devices of the fourth trigger pair to the second trigger pair to enable an impulse to be sent to the second trigger pair each time the fourth trigger pair operates to said "off" condition.

3. In combination, four pairs of electron discharge devices, each of said devices containing at least an anode, a cathode, and means to control conduction therebetween; circuits for applying operating potentials to the devices and including an impedance in the circuit to each anode; trigger connections cross-connecting the anodes and the conduction control means of the devices of each pair to form them into a trigger pair which will operate in "on" condition when current is conducted in one of the devices and in "off" condition when current is conducted in the other of the devices; circuits connecting the trigger pairs in cascade, the cascade circuits between trigger pairs extending from the anode of

said other device of a pair to the conduction control means of both devices of the next pair of the cascade, for transmitting the anode potential drop, as the trigger pair turns to its "off" condition, to the next trigger pair to cause an operation thereof, the cascade circuits between the first and second trigger pairs and the second and third trigger pairs including an isolation impedance in series with each of the conduction control means of the devices in the second and third trigger pairs; means to apply input impulses to the conduction control means of the first trigger pair; a first feed-back circuit containing a unidirectional device and extending from a mid-point of the anode impedance of the other device of the fourth trigger pair directly to the conduction control means of the other device of the second trigger pair of the cascade whereby to enable a portion of the impulse which is generated across the impedance to be applied directly to the conduction control means of the other device of the second pair to turn the second trigger pair to "on" condition each time the fourth pair goes from "on" to "off" condition; a second feed-back circuit containing a unidirectional device and extending from a mid-point of the anode impedance of the one device of the fourth trigger pair directly to the conduction control means of the other device of the third trigger pair of the cascade whereby to enable a portion of the impulse which is generated across that impedance to be applied directly to the conduction control means of the other device of the third trigger pair to turn the third trigger pair to "on" condition each time the fourth trigger pair goes from "off" to "on" condition; said trigger connections, cascade connections, and feed-back connections enabling the trigger pairs to count in the decimal notation and represent digits "1" to "9" and "0" by combinations of their "on" and "off" conditions.

4. In a device for counting in the decimal notation, the combination of four pairs of electron discharge devices, each of said devices containing at least an anode, a cathode, and means to control conduction therebetween; circuits for applying operating potentials to the devices and including an impedance element in the circuit to each anode; trigger connections cross-connecting the anodes and conduction control means of the devices of each pair to form them into a trigger pair which will operate in "on" condition when current is conducted in one of the devices and in "off" condition when current is conducted in the other of the devices, the trigger pairs by combinations of "on" and "off" conditions representing the digits "0" and "1" to "9"; circuits connecting the trigger pairs in cascade, the cascade circuits between trigger pairs extending from the anode of said other device of a pair to the conduction control means of both devices of the next pair of the cascade, for transmitting the full anode potential drop, as the trigger pair turns to its "off" condition, to the next trigger pair to cause an operation thereof, the cascade circuits between the first and second trigger pairs and second and third trigger pairs including an isolation impedance element in series with each of the conduction control means of the devices in the second and third trigger pairs; means to preset the first, third, and fourth pairs to "on" condition and the second pair to "off" condition; means to apply input impulses to the conduction control means of the first trigger pair; a first feed-back circuit extending from the mid-point of the anode im-

pedance element of the other device of the fourth trigger pair directly to the conduction control means of the other device of the second trigger pair whereby to enable half of the impulse which is generated across the anode impedance element of the other device of the fourth pair each time the fourth pair goes from "on" to "off" condition to be applied directly to the conduction control means of the other device of the second pair to turn the second pair to "on" condition, said feed-back circuit including a barrier-layer rectifier which is oriented to have a low impedance to negative feed-back impulses from the fourth trigger pair but a high impedance to negative impulses from the second pair; a second feed-back circuit extending from the mid-point of the anode impedance element of the one device of the fourth trigger pair directly to the conduction control means of the other device of the third trigger pair, whereby to enable half of the impulse which is generated across the anode impedance element of said one device of the fourth trigger pair, each time the fourth pair goes from "off" to "on" condition, to be applied to the conduction control means of the other device of the third pair to turn the third pair to "on" condition, said second feed-back circuit including a barrier-layer rectifier which is oriented to have a low impedance to negative feed-back impulses from the fourth trigger pair but a high impedance to negative impulses from the third pair; the isolation impedance elements in the circuits to the conduction control means of the second and third pairs attenuating the effect of the feed-back impulses on the conduction control means of said one tubes of these pairs and enabling half of the amount of impulses at the anodes of the fourth pair to operate the second and third pairs, and the isolation impedance elements for the conduction control means of the other tubes of the second and third pairs and the portion of the anode impedance elements of the fourth pair between the anodes and the points to which the feed-back circuits are connected, cooperating with the rectifiers to prevent impulses applied to the second and third pairs over the cascade circuits from causing unwanted trigger operations in the fourth pair, thereby enabling small, compact barrier-layer rectifiers having lower back impedance to be used in the feed-back circuits.

5. In a device for counting in the decimal notation, the combination of four pairs of electron discharge tubes, each of said tubes containing at least an anode, a cathode, and means to control conduction therebetween; circuits for applying operating potentials to the tubes and including a resistor in the circuit to each anode; trigger connections cross-connecting the anodes and control grids of the tubes of each pair to form them into a trigger pair which will operate in "on" condition when current is conducted in one of the tubes and in "off" condition when current is conducted in the other of the tubes; circuits connecting the trigger pairs in cascade, the cascade circuits between trigger pairs extending from the anode of said other tube of a pair to the conduction control means of both tubes of the next pair of the cascade, for transmitting the full anode potential drop, as the trigger pair turns to its "off" condition, to the next trigger pair to cause an operation thereof, the cascade circuits between the first and second trigger pairs and second and third trigger pairs including an isolation resistor in series with each of the con-

duction control means of the tubes in the second and third trigger pairs; means to preset the first, third, and fourth pairs to "on" condition and the second pair to "off" condition; means to apply input impulses to the conduction control means of the first trigger pair; a first feed-back circuit extending from the mid-point of the anode resistor of the other tube of the fourth trigger pair directly to the conduction control means of the other tube of the second trigger pair whereby to enable half of the impulse which is generated across the anode resistor of the other tube of the fourth pair each time the fourth pair goes from "on" to "off" condition to be applied directly to the conduction control means of the other tube of the second pair to turn the second pair to "on" condition, said feed-back circuit including a crystal rectifier which is oriented to have a low impedance to negative feed-back impulses from the fourth trigger pair but a high impedance to negative impulses from the second pair; a second feed-back circuit extending from the mid-point of the anode resistor of the one device of the fourth trigger pair directly to the conduction control means of the other device of the third trigger pair, whereby to enable half of the impulse which is generated across the anode resistor of said one device of the fourth trigger pair, each time the fourth pair goes from "off" to "on" condition, to be applied to the conduction control means of the other device of the third pair to turn the third pair to "on" condition, said second feed-back circuit including a crystal rectifier which is oriented to have a low impedance to negative feed-back impulses from the fourth trigger pair but a high impedance to negative impulses from the third pair; the isolation resistors in the circuits to the conduction control means of the second and third pairs attenuating the effect of the feed-back impulses on the conduction control means of said one tubes of these pairs and enabling half of the impulses at the

anodes of the fourth pair to operate the second and third pairs, and the isolation resistor for the conduction control means of the other tubes of the second and third pairs and the portion of the anode resistor of the fourth pair between the anodes and the points to which the feed-back circuits are connected being in series with the rectifiers between the source of impulses applied over the trigger and cascade circuits to the conduction control means of the second and third pairs and the trigger circuits of the fourth pair and cooperating with the rectifiers to prevent these impulses from causing unwanted trigger operations in the fourth pair, whereby small compact crystal rectifiers having lower back impedance can be used in the feed-back circuits; and said trigger connections, cascade connections, and feed-back connections enabling the trigger pairs to count in the decimal notation and represent the digit notation "1" to "9" and "0" by combinations of their "on" and "off" conditions.
